(57) **CLAIM**

The ornamental design for an “objective/lens for infrared camera and thermal imager,” as shown and described.

DESCRIPTION

FIG. 1 is a front perspective view of an objective for an infrared camera and thermal imager showing my new design; FIG. 2 is a front elevational view thereof; FIG. 3 is a top plan view thereof; FIG. 4 is a right side elevational view thereof; FIG. 5 is a left side elevational view thereof; and, FIG. 6 is a rear elevational view thereof, the portions in broken lines are shown for illustrative purposes only and form no part of the claimed design.
